UNITED STATES PATENT OFFICE.

GEORGE NEWTON BALL, OF ARGENTINE, MICHIGAN, ASSIGNOR OF ONE-HALF TO SYLVESTER SMITH, OF SAME PLACE.

WINDMILL.

SPECIFICATION forming part of Letters Patent No. 426,162, dated April 22, 1890.

Application filed October 20, 1888. Renewed March 25, 1890. Serial No. 345,257. (No model.)

To all whom it may concern:

Be it known that I, GEORGE NEWTON BALL, a citizen of the United States, residing at Argentine, in the county of Genesee and State of Michigan, have invented a new and useful Improvement in Windmills, of which the following is a specification.

The invention relates to windmills having horizontal wheels; and it consists in the construction and novel combination of parts hereinafter described, illustrated in the accompanying drawings, and pointed out in the claims hereto appended.

In the drawings, Figure 1 is a perspective view of a windmill embodying the invention. Fig. 2 is a central vertical section thereof. Fig. 3 is a plan view of the upper part of the windmill with the roof removed. Fig. 4 is a detail view of one of the vertical standards, showing the manner of raising the cylindrical housing. Fig. 5 is a detail view of pitman H and block I.

Referring to the drawings by letter, A designates the mill-tower, of the usual pyramidal shape and having the four upwardly-converging corner-posts a, to which are secured at their upper ends the vertical standards B, having their outer surfaces rounded, as shown, on the arc of a circle the center of which lies in the axis of the tower. The said standards are crowned by a conical roof C, the edge of which projects outward and downward, forming the eaves c.

D is the wind-wheel, composed of the four equidistant sections d, standing at right angles to each other, and the shaft E, journaled above and below at the intersections of cross-beams e, connecting diagonally the tops of the standards and the tops of the end posts. The sections d are of plate metal, preferably, and each is bent into an approximately semi-cylindrical shape and has its central part curved outward above and below to form a strengthening-rib d', that extends outward from the shaft E.

F F are collars secured to the shaft E at suitable points and having the inner lapping corners of the sections d firmly secured to their inner surfaces. The lower end of the shaft E projects below its bearing, and is squared for insertion in a squared recess in the upper end of a vertical crank-shaft G,

the lower end of which is suitably stepped upon a cross-beam of the tower.

H is a pitman standing outward from the crank g of the shaft G, and having a fork h at its outer end.

I is a block trunnioned at its ends in the arms of said fork and having a central bearing-opening.

J is a crank-lever pivoted at its angle upon a cross-beam of the tower, and with the end of its vertical arm seated in the bearing of the block I, which arm works in the notch or slot of a guide-bar j, secured at a proper point to the tower. The end of the horizontal and preferably shorter arm of the crank-lever is loosely connected by a pitman or otherwise to the upper end of the plunger-rod K, which reciprocates in suitable guides secured to the tower. The said plunger-rod may, by means of suitable connective mechanism, run a pump, a mill, or other machine.

L is a cylindrical housing, somewhat wider than the wind-wheel and adapted to slide up and down on the standards B, to the outer sides of which its curvature conforms. The said housing is provided on its interior, near its lower edge and at diametrically-opposite points, with staples l, situated near two diagonally-opposite standards.

M is a chain or rope with its ends secured to said staples, whence it passes up along the corresponding standards and over the pulleys m attached thereto, and then down again along the standards to points below the wheel, its central portion extending across within the tower.

N is a wire secured at its upper end to the middle of the chain and with its lower end within reach of the operator. By means of said chain and wire the housing may be pulled up until it is in contact with the eaves c and entirely surrounds the wheel, thereby cutting off the wind and stopping the operation of the mill. When so raised, the lower end of the wire may be attached to a cleat or other suitable detent secured to the tower.

When it is desired to start the mill, the wire is released and the housing will descend below the wheel by gravity till its lower edge rests on the stop-supports O O, secured to the corner-posts.

Whatever wind there is in any direction

will operate the mill, as the concave inner surfaces of the sections will hold the wind, while their convex outer surfaces deflect the same both upward and downward, so that 5. said concave surfaces will move with the wind and force the convex surfaces of the opposite sections against the same.

Having described my invention, I claim—
The combination of the tower, the wheel 10 arranged above the same and having a central shaft E, the crank-shaft G, having its lower end stepped on a cross-beam of the tower and its upper end engaging the lower end of the shaft E, the pitman H, projecting 15 horizontally from the crank of the shaft G and having a fork h at its outer end, the

block I, trunnioned in said fork, the crank-lever J, pivoted at its angle upon a cross-beam of the tower and having the end of its longer vertical arm engaging the block I, the 20 plunger-rod K, pivoted at its upper end to the end of the horizontal arm of said lever, and the slotted guide-bar j, secured to the tower and receiving the longer vertical arm of said lever, as specified.

In testimony that I claim the foregoing as my own I have hereto affixed my signature in presence of two witnesses.

GEORGE NEWTON BALL.
